UNITED STATES PATENT OFFICE.

OSCAR F. FORSBERG, OF YONKERS, NEW YORK, ASSIGNOR TO WESTERN ELECTRIC COMPANY, INCORPORATED, OF NEW YORK, N. Y., A CORPORATION OF NEW YORK.

SWITCHING DEVICE.

Application filed July 2, 1921. Serial No. 482,106.

To all whom it may concern:

Be it known that I, OSCAR F. FORSBERG, a citizen of the United States, residing at Yonkers, in the county of Westchester, 5 State of New York, have invented certain new and useful Improvements in Switching Devices, of which the following is a full, clear, concise, and exact description.

This invention relates in general to 10 switching devices and more particularly to such devices for use in connection with telephone or signaling systems in which circuit conditions require simultaneous closing of a large number of electrical circuits. A 15 switch of this type is particularly suited for use as a line finder or district finder in automatic telephone systems, but its operation is such that it may be used effectively in various kinds of circuits where 20 the conditions require the simultaneous closing of a large number of contacts.

It is the principal object of the present invention to provide a multiple type of switch which is cheap to manufacture and 25 one in which the maintenance cost in service will be low. Another object of the invention is to provide a structure built up in unit construction so that the parts may be readily replaced without interfering 30 with the service for any considerable length of time.

To accomplish these objects the invention provides a multiple contact relay in which the contact springs or wires are caused to 35 make contact directly with contact wires which are common to the various units of the structure, and which are preferably arranged in the form of a wire grid in operative relation to the individual contact 40 wires, means being provided for insuring a wiping contact between the contact members as they are brought in engagement.

These and other features of the invention may be more clearly understood by reference to the accompanying drawing, in 45 which Fig. 1 is a front elevation of a relay embodying the features of this invention; Fig. 2 is a sectional view taken along the line 2, 2 of Fig. 1, showing the relation 50 of the individual contact wires to the wire grid; Fig. 3 is a perspective view partly in cross-section, showing more clearly the structure of the device and the manner in which the various parts are coordinated;

Fig. 4 is a view of an individual camming 55 plate; Fig. 5 shows the manner in which the contact wires are imbedded in the insulating strip; Fig. 6 is a view of the circuit-controlling springs; Fig. 7 shows the electromagnet armature; Fig. 8 shows more 60 clearly the wiping contact or shearing effect present when using a woven wire grid; and Fig. 9 is an enlarged view showing the manner in which the wiping contact is brought about by means of the camming 65 plate.

Referring more particularly to Fig. 1, there is disclosed a relay structure comprising two independent sections each consisting of sixteen sets of twenty-five contact 70 wires, adapted to engage with the corresponding contact wire multiple. This structure comprises an upper angle mounting plate 10 and lower angle mounting plate 11, which are rigidly held together by means 75 of side plates 12, 12, which are riveted or otherwise fastened thereto. Located upon the front side of plates 10 and 11 and secured thereto by means of the screws 13, 13 are the grids, the construction of which 80 is clearly shown in Figs. 1, 2 and 3. Each grid comprises a plurality of spaced strips 14, 14 of insulating material, such for example as phenol fiber or hard rubber, the ends of which are secured between clamping plates 15, 15 and 16, 16 which are clamped together by means of screws 17, 17. The insulating strips 14, 14 which are provided with uniformly spaced notches, as 85 shown, serve as the woof of the grid, and the contact wires 18, 18 of phosphor bronze or similar material, which serve as the warp of the grid, are woven, as shown, in notches of the individual strips.

Securely mounted to the back of mounting plates 10 and 11 are the electromagnets 20, 20, these mounting plates also serving as return pole pieces for the electromagnets. Also secured to the top and bottom of plates 10 and 11, by means of screws 19, are the 100 plates 21 which are provided at the rear with openings 22, 22 through which extend the L-shaped armatures 23 of the electromagnets 20. In the front ends of these plates, and positioned in alignment with the center between openings 22, 22 are the extensions 24, 24, which in one plate are staggered with respect to the similar extensions of the other

plate. The free ends of the armatures 23 are formed, as shown, and each is provided with a transverse slot 25 having a perforation 26 centrally located therein.

5 Suspended between each armature 23 and the extension 24 which is in vertical alignment therewith, is a camming plate 27 of insulating material, such as phenol fiber. This plate is provided at one end with a supporting member 28, which is threaded to pass through the perforation 26 and is provided with an adjusting nut 29 having a knife-edge portion adapted to cooperate with the slot 25 in the armature and prevent rotation. 10 The other end of this plate is provided with a helical spring 30 which is adapted to hook over the end of extension 24. Each camming plate 27 is provided with a series of alternate slots 31, 31, extending in opposite directions 15 with respect to the vertical plane of the plate.

Secured to the side plates 12, 12 are the horizontal mounting plates 32, 32, to which are securely riveted spring plates of phosphor bronze or similar material, these plates being provided with T-shaped extensions 33, 33. The extensions 33 serve to hold in position a contact unit comprising an insulating bar 34, in which are secured the individual contact wires 35, 35. These wires which are preferably provided with a crimped portion which is molded directly into the bar 34, as shown in Fig. 5, are provided with bent-back portions or hooks 36 to facilitate the soldering of connections. The free ends of the contact wires 35, 35 are adapted to thread through the slots 31 in camming bar 27 and lie between the insulating strips 14, 14 and between adjacent wires 40 18, 18.

The contact wires are preferably secured to bar 34 in such a way that their normal tendency is to bear against their respective grid wires with the desired contact pressure. 45 In the normal or unoperated position of the camming plate, the contact wires are restrained from making contact, but upon operation of the camming plate, they are permitted to move into engagement with the grid wires. Such an arrangement makes it possible during manufacture to position the wires 35 at such an angle to the bar 34 that upon operation, the desired contact pressure is obtained without any further adjustment 50 of the individual contact wires. Moreover, with such an arrangement, the camming plate is suspended freely in position in a balanced condition, the pull of the helical spring 30 being counterbalanced by the combined tension of the contact springs, acting against the camming plate, thus maintaining the camming plate in position without any guiding means which would add friction to the structure.

60 65 The armatures 23, as shown, are adapted

to be positioned so as to pivot on the outer rear edge of plates 10 and 11, and are held in position by means of the screws 38 and nuts 39, cooperating with the formed plate 40. This plate is provided at one end 70 with a right-angled extension 41 adapted to fit within the slots 42 in plate 21, and at its other end is mounted a spring pile comprising contact springs 43, 43 between which are provided insulating spacers 44, of phenol fiber or similar material, the entire assembly being held together by means of clamping plate 45 and screws 46. The armature is also provided with an insulating stud 47, which engages the free end of one of the contact 80 springs 43, and causes opening and closing of the contacts upon movement of the armature. The air-gap adjustment of the armature is obtained by means of screw 48, which is threaded into the armature and adapted 85 to bear against the clamping plates 10 or 11. This screw is provided with a lock-nut 49 to prevent any change of adjustment during service. A proper adjustment of the camming bar, with respect to the grid, is obtained by means of the adjusting nut 29, and the knife-edged portion of this nut not only provides a locking feature but also allows the plate to ride freely upon the armature without any binding. 95

In operation the energization of one of the electromagnets causes its armature to be attracted, thus resulting in a movement of the corresponding camming plate 27 against the tension of the retractile spring 30. The wires 35 thus move under their own tension into engagement with cooperating wires 18 of the grid, and since the slots 31 are oblique to the direction of movement, the ends of wires 35 are displaced horizontally, thus causing a wiping or rubbing action on the wires 18, as clearly shown in Fig. 9 of the drawing in which the position of wires 35 under normal conditions is shown in full lines, and the corresponding position when operated is shown by dotted lines, the arrows representing the direction and also the distance of the horizontal movement of the wires 35. It will be noted that when the camming plate 27 is drawn upward by its operating magnet, the upper wire 35 moves vertically until it engages with the upper wire 18, and the direction of the slot 31 is such that for the balance of the movement of plate 27, the wire 35 is held in contact with the wire 18 and moves horizontally to the right. In the case of the lower wire 18 illustrated in this figure, the wire first moves into engagement with the lower wire 18 and the direction of the corresponding slot in plate 27 is such as to cause the wire 18 to then move horizontally to the left. By thus employing slots running in opposite directions, it is possible to entirely eliminate the side thrust which would otherwise 100 105 110 115 120 125 130

be present and would be of considerable magnitude in case of a relay having a large number of contact wires, each wire being under sufficient contact pressure to insure a satisfactory contact. Furthermore, since the grid wires are woven, there is also provided a shearing action which results in a wiping along the wires 35, as will be seen more clearly by referring particularly to Fig. 8.

With the arrangement of the parts as shown, when the wire 35 moves horizontally to the right to take up the position shown by the dotted lines, its point of contact has varied a distance somewhat greater than the thickness of the insulating strips 14, thus causing a rubbing action on the wire 35 as well as on the wire 18. This combined shearing and wiping effect serves very efficiently to insure a low resistance contact between the individual contact wires and the grid wires.

The grids are made up as a unit and are held in position by means of screws 13, 13. Thus, in case of injury to the grid or any defects which may become apparent, it is possible to very quickly and very easily remove the grid and replace it with another. The wire contact springs 35 are also arranged so as to be easily replaced since by spreading apart the spring extensions 33, 33 at the top and bottom, the entire unit may be quickly removed and another substituted. The camming plates are also so arranged as to be easily interchangeable and are freely suspended between the grid and the mounting plates, the self-locking adjustment described above being provided for obtaining the proper position of the plates with respect to the grids. By staggering electromagnets, that is, having the operating magnet for adjacent bars positioned alternately at the top and bottom of the device, a structure is provided which is very compact.

What is claimed is:

1. In a switching device, a set of passive contact members comprising bare wires arranged in woven grid formation, a set of active bare wire contact members coordinately disposed to other said set, and means for causing the active wires to move in one operation in two directions at right angles to each other, the initial motion of the active wires causing them to engage the passive wires, the continued motion of the active wires causing them to vary the point of engagement with said passive wires.

2. In a switching device a grid unit comprising a plurality of parallel conductors insulated from each other, a plurality of other conductors fixed at one end and substantially perpendicular to said grid and having their free ends extending between the conductors thereof, and means for moving said other conductors into engagement

with the conductors of said grid and providing a wiping action on each of said conductors.

3. In a switching device a grid unit comprising a plurality of bare wires supported on notched insulating strips, a plurality of conducting springs having their free ends extending between adjacent wires of said grid, a camming plate adapted to permit said conducting springs to move simultaneously into engagement with the wires of the grid, and means for causing the operation of the camming plate.

4. In a switching device a grid unit comprising a plurality of bare wires supported on insulating strips, a plurality of conducting springs having their free ends extending between adjacent wires of said grid, a camming plate provided with a plurality of oblique slots through which the free ends of said conducting springs extend, and an electromagnet for causing the movement of said plate whereby the conducting springs are moved with a wiping action into engagement with the wires of said grid.

5. In a switching device a grid unit comprising a plurality of bare wires supported on notched insulating strips, a plurality of conducting springs having their free ends extending between adjacent wires of said grid, a camming plate provided with a plurality of oblique slots through which the free ends of said conducting springs extend, adjacent slots being formed in said plate in opposite directions substantially as shown to neutralize side thrust, and an electromagnet for causing the movement of said plate whereby the conducting springs are moved with a wiping action into engagement with the wires of said grid.

6. In a switching device a mounting frame, a woven grid unit fixedly mounted on said frame, a plurality of sets of resilient contact members interchangeably mounted on said frame each of said sets comprising a stationary insulating bar having a plurality of conducting springs rigidly secured therein, and means for flexing said contact members.

7. In a switching device a mounting frame, a grid unit mounted on said frame, a plurality of sets of contact members interchangeably mounted on said frame each of said sets comprising an insulating bar having a plurality of conducting springs rigidly secured therein, and spring means for locking said bars in place.

8. In a switching device a grid unit comprising a plurality of parallel conductors insulated from each other, a camming plate provided with a plurality of slots mounted adjacent said grid unit, a plurality of conducting wires having their free ends extending through the slots in said camming plate and between the adjacent wires of the

- grid unit, and means for moving said camming plate to cause said wires to move into engagement with the wires of the grid.
9. In a switching device a grid unit comprising a plurality of parallel conductors insulated from each other, a camming plate provided with a plurality of slots mounted adjacent said grid unit, a plurality of conducting wires having their free ends extending through the slots in said camming plate and between the adjacent wires of the grid unit, an electromagnet for causing the movement of said camming plate, and adjustable means for changing the normal position of said camming plate with respect to the grid.
10. In a switching device a grid unit comprising a plurality of parallel conductors insulated from each other, a camming plate provided with a plurality of slots mounted adjacent said grid unit, an electromagnet for causing the movement of said camming plate, and adjustable self-locking means for changing the normal position of said camming plate with respect to the grid.
11. In a switching device a mounting frame, a grid unit on said frame, said unit comprising a plurality of conductors insulated from each other, a plurality of conducting springs mounted on said frame perpendicular to the plane of the grid unit, and means for moving said springs into engagement with the grid conductors.
12. In a switching device a mounting frame, a grid unit removably mounted on said frame, said grid comprising a plurality of parallel conductors insulated from each other, a plurality of conducting springs mounted on said frame perpendicular to the plane of the grid unit, and means for moving said springs into engagement with the grid conductors.
13. In a switching device a mounting frame, a grid unit removably mounted on said frame, said unit comprising a plurality of conductors insulated from each other, a plurality of conducting springs mounted on said frame perpendicular to the plane of the grid unit and having their free ends extending between adjacent conductors, and means for moving said springs into engagement with the grid conductors.
14. In a switching device a mounting frame, a woven wire grid removably mounted on said frame, said grid unit comprising a plurality of parallel wire conductors insulated from each other, a plurality of conducting springs mounted on said frame perpendicular to the plane of the grid unit, and means for moving said springs into engagement with the grid conductors.
15. In a switching device a mounting frame, a removable grid unit mounted on said frame, said unit comprising a fabric of bare wires forming the warp and rigid insulating strips forming the woof, a plurality of conducting springs mounted on said frame perpendicular to the plane of the grid unit, and means for causing said springs to engage the wires of the grid.
16. In a switching device, a mounting frame, a grid unit replaceably mounted on the front of said frame, a plurality of sets of contact members mounted within said frame, each set of contact members comprising a plurality of contact wires having their free ends perpendicular to the plane of said grid, a camming plate having oblique slots therein through which the free ends of said contact wires extend, and an individual electromagnet for each of said camming plates mounted within said frame and utilizing the frame as a return pole piece.
17. In a switching device, a woven wire grid, a set of active wires with their ends extending through the grid, an operating member normally holding the active wires under tension and out of engagement with the grid wires, and means for actuating said member to effect engagement between the active wires and the grid wires.
18. In a switching device a set of contact members, a second set of bare contact members normally tensioned to engage said first set of contact members, means for normally maintaining said contact members out of engagement, said means upon operation cooperating with the tension of the bare wire conductors to permit them to move into engagement with the set of contact members with a wiping action.
19. In a switching device a grid unit comprising a plurality of parallel conductors insulated from each other, a plurality of conductors mounted substantially perpendicular to said grid and having their free ends extending between the wires thereof, said conductors being normally tensioned to engage said grid wires, means for controlling the movement of said wires, and spring means for maintaining said controlling means in a balanced condition against the combined tension of the conductors.
20. In a switching device, a grid consisting of conductors woven with insulating strips, a set of active conductors mounted with their free ends extending into cooperative relation with said grid conductors, and means for flexing the active conductors to move them into engagement with said grid conductors.
21. In a switching device, a woven wire grid, a set of active wires mounted with their free ends extending through the grid to cooperate with said woven wires, and means for causing the active wires to move into contact with the grid wires.
22. In a switching device, a woven wire grid made up of passive wires and insulating strips, a plurality of active wires having

- their ends extending through said grid to cooperate with said passive wires, an operating member having slots in which the active wires are held under tension and 5 out of contact with the passive wires, and means for moving said member to release the active wires into engagement with the passive wires of the grid, said slots causing the active wires to wipe over the passive 10 wires.
23. In a switching device, a woven wire grid, a plurality of active contact wires mounted with their free ends projecting through said grid, an operating member having diagonal slots through which the active 15 wires extend, said active wires being held normally by said member under tension and disengaged from the grid wires, and means for moving the operating member, the initial 20 movement of said member releasing the active wires into contact with the grid wires, the continued movement of the operating member causing the active wires through the action of said slots to wipe over the grid 25 wires.
24. In a switching device, a woven wire grid, a plurality of sets of active contact wires mounted with their free ends extending through the grid to cooperate with said 30 woven wires, and means for causing any set of active wires to move into contact with the woven wires of the grid.
25. In a switching device, a woven wire grid, a plurality of sets of active contact 35 wires mounted with their free ends normally extending through and in operative
- relation with the grid wires, and individual electromagnets for causing the operation independently of any set of active wires to engage the grid wires with a wiping action. 40
26. In a switching device, a contact grid comprising insulating elements and a plurality of curved conductors supported by said elements, active conductors normally extending through said grid into cooperative relation with the grid conductors, and means for causing the active conductors to move into contact with said grid conductors, the curvature of the grid conductors causing a wiping action between them and the active conductors. 45
27. In a switching device, a plurality of insulating elements, passive conductors woven in and out with the insulating elements, active conductors mounted with their free ends extending into cooperative relation with the passive conductors, and means for causing the active conductors to engage and wipe over a portion of the length of the passive conductors, the disposition of said 50 passive conductors due to weaving causing a wiping action over a portion of the length of the active conductors. 55
28. A switch comprising movable contacts, fixed contacts, and means for moving said first contacts in a plane at right angles to the plane of said fixed contacts and along the length thereof, whereby a wiping engagement is effected between said contacts. 60
- In witness whereof, I hereunto subscribe my name this 28th day of June A. D., 1921.
OSCAR F. FORSBERG.
